UNITED STATES PATENT OFFICE

JAMES K. DIAMOND, OF GRAND RAPIDS, MICHIGAN, ASSIGNOR TO CLIPPER BELT LACER COMPANY, OF GRAND RAPIDS, MICHIGAN, A CORPORATION OF MICHIGAN

BELT CLIP CARD

Application filed June 29, 1931. Serial No. 547,682.

This invention relates to belt clip cards and more particularly to the temporary cards on which the belt clips are mounted for handling prior to actual use.

5 Although the invention is specifically shown and described herein as applied to so-called belt clips which are wire devices applied to the respective ends of power transmitting belts whereby a series of loops or eyes is provided at each end of the belt through which a pin is inserted to join the ends, the invention is applicable for use in connection with other analogous devices.

10 The belt clips as manufactured and sold to be applied to belts are in the nature of wire devices bent between their ends to form the bend of what will eventually be a loop or eye and at each side of the bend straight sides extend divergently each having pointed ends 15 extending inwardly. The clips are to be attached to an end of a belt in spaced relation by use of a machine which receives a series of clips and compresses the pointed ends into the belt and clinches them.

20 It has been customary in this art to mount the clips at the time they are manufactured on so-called cards in the proper relative positions and spaced apart locations that they will eventually be used when applied to the belt, such a card being in the nature of a 25 cardboard channel member having a base and sides which sides are upwardly converging to lie within the corresponding diverging portions of the clips and the points of the 30 clips pierce the sides of the cardboard channel thereby retaining the clips on the card and holding them in proper spaced relation. The clips are usually placed on the card by collapsing the channel, probably by flexing 35 its base so that the sides may be inserted over the prongs or points of the clips.

40 Such a manner of carding the clips has had the disadvantage that anything excepting careful handling would cause the sides of the 45 channels to bend inwardly or the base of the channel, which had previously been flexed and therefore lost its stiffness, would readily flex whereby the card would often inadvertently disengage from the clips. It is the 50 object of this invention to provide a simple

efficient and inexpensive means for retaining the cardboard channel on the clips so that ordinary rough usage will not displace it and to provide as an additional feature a convenient means for measuring a series of clips 55 to be applied to the end of a belt. The device provides various novel features of construction and arrangement as hereinafter more fully described and particularly pointed out in the claims, reference being had to the accompanying drawing, in which,

Fig. 1 is a perspective view of a group of 60 cards embodying this invention.

Fig. 2 is an enlarged cross sectional view 65 showing the manner of applying the cardboard channel to the clips.

Fig. 3 is a view similar to Fig. 2 showing the channel applied and the reinforcing member of this invention in proper operative position.

Fig. 4 is a side elevation of a small section 70 of carded clips.

Fig. 5 is a reduced size plan view of carded 75 clips showing the reinforcing member of this invention partially withdrawn and serving as a measuring device, and

Fig. 6 is a plan view of the reinforcing member of this invention removed from other parts of the structure.

Like reference numbers refer to like parts 80 in all of the views.

1 represents the clips, each of which comprises a short piece of wire bent between its ends at 2 and having side portions 3 extending divergently at each side of the bend 2 and each side portion terminates in a pointed end or prong 4 bent inwardly. It is customary to have one of the sides 3 longer than the other and the clips arranged in alternately reversed positions so that the prongs of the series of 85 clips are staggered.

The card on which the clips are mounted 90 comprises a channel made of cardboard or similar material having a base 5 and sides 6, which sides extend upwardly from the base in a converging direction. The base of the channel is substantially the same width as the distance between the lower longer ends 2 of the series of clips and the sides 6 of the channel may be provided with openings 7 to re-

ceive the prongs 4 of the clips or such openings may be pierced by the prongs themselves when the channel is inserted on the clips.

Inasmuch as the distance between the points of the series of clips is greatly less than the width of the channel, making it impossible to insert the sides of the channel between the points for placement of said points in the openings of said sides, it is necessary to distort the channel when it is applied and this is commonly done by flexing the base 5 thereof as shown in Fig. 2, which permits said sides to be readily inserted between the points of said clips after which the sides may be spread apart by straightening the base 5 as shown in Fig. 3. When this is done the prongs 4 of the clips are inserted in the openings 7 in the sides of the channel or the prongs have pierced the sides of the channel making their own openings therein, the said sides of the channel lie convergently against the sides 3 of the clips and the base has again assumed its substantially straight position.

However, as previously described, the base 5 is made of cardboard and having once been flexed has lost considerable of its rigidity and may easily be again flexed out of straight position which would cause the sides of the channel to remove from the prongs 4 which has often inadvertently happened. To prevent such an occurrence a reinforcing member 8 is provided in the nature of a flat elongated cardboard strip which is inserted between the sides 6 of the cardboard channel at a point spaced above the base and the inherent stiffness of such strip 8 which has never been bent out of its flat condition strongly resists any tendency for the sides 6 of the channel to move inwardly. The width of the strip 8 is substantially the same as the distance between the sides 6 at the vertical location in which the strip is placed. It is preferable in this structure to locate the strip between the upper and lower rows of the points 4, which points will properly locate the strip 8 in position. The strip 8 is the length of a carded series of clips.

It is preferable to have the strip 8 indexed throughout its length with marks 9 indicating measurements such as inches and fractions thereof. Such index marks 9 may readily be printed on one surface of the strip and thus equip the strip 8 to be used as a means for measuring the length of a series of carded clips to be cut from the card for use.

It is customary to provide a series of carded clips having a length in excess of the width of the belt to which they are to be applied and it is common practice to remove from a card of clips by cutting from the card a series of clips the proper length to extend across the end of a belt. By utilizing the measurement indexes on the strip 8 the strip may be slid from the card to expose the indexes indicating the desired measurement of

the length of the series of clips to be used and then the card may be severed directly opposite the inner end of the strip 8 which will remove a section of clips the exact length desired.

It will be seen that this invention provides a most simple, cheap and efficient means for reinforcing the channel card on which the clips are mounted and also provides a ready device for measuring the length of section to be removed. The strip 8, being simply an elongated flat strip of cardboard, is very cheap and adds very little to the expense of carding the clips. Printing the measurement indexes thereon also is a very cheap operation. The strip is applied by simply inserting it endwise into the channel after the clips have been applied thereto.

The location of the strip between the upper and lower rows of prongs 4 effectively retains it in its proper position. In this respect the lower rows of prongs 4 are more essential in locating the strip than the upper rows because they hold the strip placed above the base 5 of the channel. The inwardly converging sides 6 of the channel could be utilized entirely to prevent the strip from rising out of its proper location. It would also be practicable to locate the strip above the upper row of prongs 4 and to rely upon the turned sides 6 of the channel to prevent it moving upwardly out of place.

The longitudinal edges of the strip 8 lie closely against the sides 6 of the channel and because of the inherent stiffness of the strip 8 said sides cannot readily be moved inwardly. In use the operator may measure the width of the belt to which the clips are to be applied and then slide the strip from one end of the channel to expose the index marks 9 thereon indicating the length of the section to be removed after which the section may be cut from the card adjacent the inner end of the strip. This measuring and cutting operation can be repeated as long as any of the length of carded clips remains.

The drawing illustrates the upper edge of one of the sides 6 of the channel as being slotted at 10 and turned outwardly to embrace the sides 3 of the clips. This feature is for the purpose of preventing the clips turning out of their proper vertical positions but this detail has no bearing on the present invention which is fully effective with or without it.

The invention defined in the appended claims is to be considered comprehensive of all forms of structure coming within their scope.

I claim:

1. In a device of the class described, a channel shaped carding member of flexible material having a base and spaced apart sides, devices mounted on said sides having parts extending therethrough from the outside in

wardly, said parts projecting beyond the inner surfaces of said sides and a stiffening member supported by said inwardly projecting parts and located in spaced apart relation with said base at its contacting edges, said stiffening member extending between said sides and being substantially the width of the distance between said sides.

2. In a device of the class described, a carding member of flexible material comprising a channel having a base and upwardly converging sides, devices mounted on said sides having parts extending therethrough from the outside inwardly, said parts projecting beyond the inner surfaces of said sides and a stiffening member supported in spaced apart relation with said base upon said inwardly projecting parts, said stiffening member being substantially the width of the distance between said sides at the point where it is located and being wider than said sides at a point above its location.

3. In a device of the class described, a carding member of flexible material comprising a channel having a base and upwardly converging sides, devices mounted on said sides having parts extending therethrough from the outside inwardly, said parts projecting beyond the inner surfaces of said sides and a stiffening member comprising a flat strip supported in spaced apart relation with said base upon said inwardly projecting parts, said stiffening member being substantially the width of the distance between said sides at the point where it is located and being wider than said sides at a point above its location.

4. In a device of the class described, a carding member made of flexible material having upwardly converging sides, devices mounted on said sides having parts projecting therethrough a short distance from the outside inwardly, said parts projecting beyond the inner surface of said sides and a stiffening member positioned by said inwardly projecting parts and extending between said sides in a position to prevent their movement toward each other for the purpose described.

5. In combination with a plurality of belt clips having spaced apart opposing pointed prongs, a carding member having spaced apart sides, the points of said prongs being adapted to have engagement with the said sides, and a reinforcing member inserted between the said sides for the purpose described.

6. A combination of elements as recited in claim 5 in which the reinforcing member is slideable and has indicia printed thereon for the purpose described.

In testimony whereof I affix my signature.
JAMES K. DIAMOND,
